Fig. 1.

Fig. 2.

Fig.3.

Fig.4.

FIG. 1 is a perspective view of a television receiver or similar article with the cabinet doors in their closed position, embodying the new design;

FIG. 2 is a perspective view of the television receiver with the doors in their opened position;

FIG. 3 is a fragmentary front elevation view of the television receiver with the cabinet doors in their closed position; and

FIG. 4 is a fragmentary side elevation view of the television receiver with the doors in their closed position.

The back, not shown, is a substantially plain, flat surface. Wavy lined portions of the drawing figures indicate contrast in appearance.

I claim:

The ornamental design for a television receiver or similar article, substantially as shown and described.
